US00D965594S

(12) **United States Design Patent** (10) Patent No.: **US D965,594 S**
(45) Date of Patent: ** Oct. 4, 2022

(54) **COMPUTER MOUSE**

(71) Applicant: **BUILT ON EXPERIENCE AB**,
Landskrona (SE)

(72) Inventors: **Zy Jay Ryko**, Coolangatta (AU); **Erik Jensen**, Dalby (SE)

(73) Assignee: **Built on Experience AB**, Landskrona (SE)

(**) Term: **15 Years**

(21) Appl. No.: **35/509,930**

(22) Filed: **Jul. 1, 2020**

(80) **Hague Agreement Data**

Int. Filing Date: **Jul. 1, 2020**

Int. Reg. No.: **DM/209315**

Int. Reg. Date: **Jul. 1, 2020**

Int. Reg. Pub. Date: **Jul. 31, 2020**

(30) **Foreign Application Priority Data**

Jun. 18, 2020 (EM) 008010169-0001

(51) LOC (13) Cl. **14-02**

(52) U.S. Cl.

USPC **D14/402**

(58) **Field of Classification Search**

USPC D14/356, 383-385, 388, 389, 402-411,
D14/417, 426

CPC .. G06F 3/033; G06F 3/038; G06F 2203/0333;
G06F 2203/0384
